G. W. JACQUES

DUPLEX EYELETING MACHINE

Filed August 26, 1920

UNITED STATES PATENT OFFICE.

GEORGE W. JACQUES, OF STRATFORD, CONNECTICUT, ASSIGNOR, BY MESNE ASSIGNMENTS, TO UNITED SHOE MACHINERY CORPORATION, OF PATERSON, NEW JERSEY, A CORPORATION OF NEW JERSEY.

DUPLEX EYELETING MACHINE.

Application filed August 26, 1920. Serial No. 406,054.

To all whom it may concern:

Be it known that I, GEORGE W. JACQUES, citizen of the United States, residing at Stratford, in the county of Fairfield and

5 State of Connecticut, have invented certain new and useful Improvements in Duplex Eyeleting Machines, of which the following is a specification, reference being had therein to the accompanying drawings.

10 This invention relates to fastener-inserting machines and more particularly to means for supplying fasteners to the inserting mechanism. For purposes of illustration the invention is disclosed by the accompanying drawings as embodied in a duplex eyeleting machine having telescopically related punches and setting tools arranged to operate on two pieces of work in confronting relation.

15 An object of the invention is to provide improvements in the construction and arrangement of the fastener-raceway and in the mechanism for operating the latter, with a view to simplifying the organization of 25 the machine, minimizing the weight of the reciprocatory parts of the fastener-supplying means, improving the action of the raceway, and affording the operative better observation of the work at the fastener-inserting locality.

20 A feature of the invention consists in an improved construction of the hopper and raceway, including a pivotal joint connecting the two and permitting the hopper and the relatively great mass of eyelets therein to remain stationary while only the raceway undergoes reciprocation to present the fasteners to the inserting mechanism. The illustrated hopper embodies the customary 35 circular form and the raceway is arranged in tangential relation thereto, while the aforesaid pivotal joint between the two is located at the tangent point. Disregarding the inclination of the raceway by which the 40 fasteners are caused to gravitate to its delivery end, the raceway is preferably arranged to extend substantially parallel to the lines of movement along which the work is fed, so that the delivery end of the raceway 45 may move from front to rear behind the inserting locality. The axis of the pivotal

joint between the raceway and hopper is therefore located close to, if slightly behind, a line passing through the inserting locality and extending parallel to the lines of feeding motion. The hopper is preferably located behind said line and the pivotal joint is therefore located at the front of the hopper.

55 Another feature consists in improved means for operating the raceway so that at high speed the operation will be smooth and regular and the least productive of vibration. The preferred type of mechanism for this purpose comprises a crank and a connecting rod because they reverse the directions of motion by gradual increments and decrements of speed. For the purposes of the present invention the connecting rod is provided with universal joints which permit 60 lateral movement to provide for angular motion of the raceway about an axis that is otherwise than parallel to the axis of the crank.

65 Still another feature consists in forming 75 the telescopically related punch and setting tool to provide an annular chamber to prevent accumulations of dust, lint and other dirt from becoming so compacted between them as to interfere with the punch's function of picking eyelets from the raceway.

70 Other features of the invention, together with advantageous details and combinations of parts will appear from a description of an embodiment thereof illustrated in the 80 accompanying drawings in which—

Fig. 1 is a fragmentary view partly in horizontal section of a portion of a duplex eyeleting machine.

Fig. 2 is a fragmentary end elevation with 90 parts removed or broken away:

Fig. 3 is a perspective of the end of the raceway.

Fig. 4 is a front elevation of the eyelet distributing hopper and raceways and their 95 immediate mountings.

Fig. 5 is a fragmentary view looking in the direction of the arrow 5 on Fig. 4.

Figs. 6 and 7 are cross sections through the telescopically combined punch and set 100 showing these members in different relative positions.

Figs. 8 and 9 are plan and elevation respectively of the delivery end of the lower raceway, and

Fig. 10 is a detail showing a connection of the raceway to the hopper.

Referring to the drawings: A represents a portion of the machine frame in which is journaled a shaft 1 carrying at its outer end an eccentric pin 2. Mounted closely adjacent to this end of the shaft 1 is a work-feeding frame member 3 which may be formed as a lever and pivoted at its rear end to swing laterally, as more fully shown in United States Letters Patent 1,434,688, granted November 7, 1922. Member 3 is forked at its forward end, the forked portions being formed as sleeves 4 and 5 for the slidable reception of the telescopically combined punches and sets shown at 6 and 7. Fixed to the frame A is a bracket 8 having a forwardly extending guide portion 9 on which may ride a roller 10 journaled near the lower end of a distributing raceway 11. As shown, this raceway is made double, to provide separate paths for the eyelets to present the same in proper position to the punching and setting mechanisms. Frame A also carries fixed thereto a bracket B having at its outer end an inclined hollow sleeve 12 within which is mounted a sleeve 13 (see Fig. 5) depending from a distributing hopper 14, a set screw 15 being provided to fix the hopper 14 from turning relative to the sleeve 12. Journaled within the sleeve 13 is a shaft 16 which may carry at its upper end any suitable or usual eyelet agitating means within the hopper 14. At one side the lower face of the hopper 14 is extended as shown at 17 and carries fixed thereto by means of the spacing bars 18 and 19 a distributor segment 20 by which the eyelets forced outward from the hopper 14 are guided into their respective ways in the raceway member 11. This raceway member is pivoted to the extension 17 at 21 and is provided with a lateral extension 22 having a slot 23 for the reception of a screw 24. As shown in Fig. 10, a washer 240 through which the screw 24 passes is urged into contact with the raceway 11 by means of a spring lock washer 241 interposed between it and the head of screw 24. This construction allows a limited pivotal movement of the raceway about an axis directly in line with the eyelet path, but at the same time holds the raceway accurately in registering position with relation to the segment 20.

Each guideway of the raceway member 11 is slotted vertically throughout the major portion of its length in order to allow lint or other foreign matter to pass therethrough without danger of clogging the eyelets therein.

The lower end of the raceway is connected to the operating crank 2 by a universally

jointed connecting rod comprising sections 25, 26 and 27. The sections are pivotally connected to each other by pivots which provide for angular movement of the raceways and for a slight component of lateral movement of the connecting rod due to the angular movement of the raceways. 70

At the end of each raceway path is mounted a retaining finger 28, shown in Fig. 3 as pivoted to the raceway at 29 and provided with a curved retaining portion 30 normally held across the open end of the raceway path by means of a spring 31 engaging between the rear end of the finger 28 and a shoulder on the raceway, an adjusting and guiding screw 32 fixed in the finger holding the spring in position. 75

Fixed to the feed frame member 3 between sleeves 4 and 5 is a forwardly extending member 33 carrying near its outer end a double ended combined punch anvil and set 34 in cooperative relation to the punch and set mechanisms 6 and 7. 80

As shown in Figs. 6 and 7, each punch and set mechanism comprises an outer sleeve 35 in one end of which is screwed a set 36. The outer face of set 36 has an annular setting surface 37 provided with an axial perforation. A punch 38 has an extended punch element 39 which projects through the central perforation of the set 36, and its rear end has formed thereon an enlarged head 40 of a diameter to slide within the sleeve 35 and to impinge against the inner end of the set 36. The punch is normally held in projected position with the head 40 in contact with the end of the set by means of a plunger 41 having a head 42 impinging on the head 40 and urged thereagainst by means of a spring 43 surrounding the plunger and bearing at its opposite end against any suitable abutment (not shown). Back of the setting surface 37 the central perforation of the set merges with an enlarged cavity 44 within which the punch element 39 may play freely, and forming therewith an annular chamber of considerable size. 90

In order to prevent the feeding of eyelets to the lower punch and set mechanism, a stop finger may be employed, this finger movable at will into and out of the path of the eyelets in the raceway. Such a construction is shown in Figs. 8 and 9, wherein 45 is a lever pivoted at 46 on the lower section of the raceway. This lever has a resilient finger portion or handle 47 movable between retaining notches or depressions 48 and 48^a in a fixed part of the raceway. The lever 45 is formed with a curved extremity 49 which is positioned in the path of the eyelets immediately back of the last eyelet when handle 47 engages notch 48, to prevent the flow of the eyelets, and which is retractable from the eyelet path by swinging the handle to engage notch 48^a. 105

The operation of this mechanism is as follows: A piece of work is fed either side of the double ended combined anvil and set 34 in position to be punched on the closing 5 of the oppositely disposed punches thereagainst, these punches being actuated in any suitable manner, by forcing together the mechanisms 6 and 7. At the start of movement of the punches to punching position, 10 the raceways are positioned to present the eyelets to the punches which pass through the barrels thereof. On further motion of the punches the raceways are retracted by the action of the eccentric pin 2, the spring 15 fingers 28 yielding to allow the threaded eyelets to pass from the ends of the raceways, these fingers thereupon closing the open ends to prevent the escape of succeeding eyelets. The mounting of the raceway 20 allows its motion to be a slight swing about the pivot 21 as a center, this pivot being so positioned that the lower ends of the raceway move to the front and rear and substantially at right angles to the line of feed. 25 By arranging the raceway so that its delivery end will swing from front to rear, and by arranging the crank 2 nearly directly behind said end of the raceway, it is possible to attach the connecting-rod directly to the 30 raceway adjacent to the delivery end. This relation of the crank and raceway permits much lighter parts than those required in prior constructions and permits high speed of operation without appreciable vibration. 35 The raceway extends substantially parallel to the axis of the crank-shaft 1, and its pivot 21 is adjacent to but behind a line intersecting the inserting locality and extending parallel to the direction of work- 40 feed, which line is represented in Fig. 5 by broken line *a*.

After the material has been punched and the raceways retracted out of the way, further motion of the punching and setting 45 mechanisms toward the work causes the setting elements to force the eyelets through the work and clinch the same against the block 34, the punches being allowed to yield by the springs 43 during this portion of 50 the operation. While these mechanisms are in engagement with the work, the carrying member 3 is moved laterally to feed the work. On the retraction of the punch and set elements, the work is freed, and the 55 frame 3 is given a return motion preparatory to a subsequent punching and setting operation.

With prior constructions including telescopically related punches and sets, it has 60 been found, particularly when working on fabrics, that lint and other foreign matter accumulates around the punch elements and is carried thereby back within the set elements, such accumulations heretofore resulting in a clogging of the punch and set and

preventing free relative movement thereof. For this reason the punches have sometimes failed to pick the eyelets from the raceways. On the other hand, by providing the dirt chambers as herein shown sufficient space is 70 allowed for a considerable accumulation before clogging is caused. As these punches break after some time in service, it has been found that this chamber may be made of sufficient size to insure against clogging during the effective life of the punch. When the punches are renewed, this chamber is 75 readily cleared of obstructing material.

If the operator wishes to use the upper punch and setting device only, as when eyelets may have been skipped, the finger portion 47 on the lower raceway portion is moved into engagement with notch 48 as shown in Fig. 8, and the end eyelet is picked out of the raceway. In subsequent operation of the machine no eyelets are presented to the end of the lower raceway in position to be picked therefrom by the lower mechanism. When it is desired to resume the duplex setting, finger portion 47 is moved 85 into engagement with notch 48^a, which allows the eyelet feed to the lower mechanism to be resumed.

While this invention has been described in connection with a duplex eyelet setting machine, it is evident that features thereof might be used with equal advantage in single machines, or many machines intended to perform other operations on material.

Having thus described certain embodiments of this invention, though it is evident that many changes and modifications may be made therein without departing from its spirit or scope, what is claimed is—

1. In a machine of the class described, fastener-inserting mechanism, a hopper for fasteners, a raceway movable relatively to said hopper and arranged to conduct fasteners from the latter to said mechanism, a pivot connecting one end of said raceway to said hopper, means arranged to support the delivery end of said raceway in cooperative relation to said mechanism, an operating crank, and a connecting rod one end of which embraces said crank and the other end of which is connected to said raceway near its delivery end.

2. In a machine of the class described, a supply hopper, operating mechanism, a main shaft, a raceway pivoted at said hopper and having its free end extending toward said mechanism, a fixed guide, a member carried by the free end of said raceway and movable on said guide, an eccentric on said shaft, and a link connecting said eccentric and the free end of said raceway.

3. A fastener-inserting machine comprising mechanism for inserting fasteners, mechanism for feeding the work, a fastener-raceway arranged to swing about an axis ad-

5. jacent to a line intersecting the inserting locality and extending parallel to the direction of work-feeding movement so that the movement of the delivery end of the raceway will be substantially at right angles to said line, and mechanism for reciprocating said raceway to move the delivery end as aforesaid.
4. In a machine of the class described, a supply hopper having an extension, a raceway pivoted to said extension and having a slotted bearing portion, a screw passing through the slot of said portion and fixed to said extension, a washer bearing on said bearing portion and through which said screw passes, and a spring member interposed between the head of said screw and said washer, whereby said raceway is resiliently held against said extension.
5. In combination, a hollow fastener set, and a punch telescopically related to said

set and of smaller diameter than the hollow of said set, to leave substantial space therebetween.

6. In combination, a sleeve, a set element made fast in one end of said sleeve and having a setting surface and a perforation centrally thereof merging with an annular recessed portion, and a punch having a punching element passing through said perforation and an enlarged head slidably mounted within said sleeve in position to impinge on the rear end of said set, said punch element being throughout of substantially smaller diameter than said recessed portion to form therewith an annular chamber of substantial width.

In testimony whereof, I have signed my name to this specification.

GEORGE W. JACQUES.
